To all whom it may concern,

Be it known that I, Myer Phineas, of the City, County and State of New York, have invented a certain new design for an Ink stand; and I do hereby declare the same to be clearly represented in the accompanying drawings, which represent my said design, in perspective.

The body A. of the inkstand is formed with polygonal sides and back which may taper very slightly upward and a wide face in front, in the centre of which is a vertical concavity a. opposite which concavity the dipping cup B. is located.

A saucer C. extends around the front from one to the other of the outer angles, c. c. beneath the dipping cup.

I claim as new and desire to secure by Letters Patent, the design for an Inkstand, represented in the accompanying drawings.

The above specification of my design for Inkstands signed this first day of February, 1862.
